UNITED STATES PATENT OFFICE.

XAVIER F. COUNARD, OF BRUSSELS, WISCONSIN.

GRADING-MACHINE.

1,276,876.

Specification of Letters Patent. Patented Aug. 27, 1918.

Application filed April 17, 1917. Serial No. 162,720.

To all whom it may concern:

Be it known that I, XAVIER F. COUNARD, a citizen of the United States of America, residing at Brussels, in the county of Door 5 and State of Wisconsin, have invented certain new and useful Improvements in Grading-Machines, of which the following is a specification, reference being had therein to the accompanying drawings.

10 The invention relates to grading machines and has for its object the provision of a machine that is mounted on wheels and includes a plurality of scraper plates adapted to level earth, such as is necessary for the construction 15 of road beds or for similar purposes.

A further object constitutes the arrangement of the scraper plate on an auxiliary frame adapted to be raised or lowered with respect to the main carrying frame of the 20 machine, and adapted to be turned from side to side so as to adjust the scraper plates with respect to the direction of movement in which the machine is conveyed.

It is also an object of the invention to provide means whereby the auxiliary frame may be turned about a centrally located pivot pin.

Still another object constitutes the provision of a single lever capable of fitting the 30 various adjustments referred to, such that an operator can conveniently raise, lower, or turn the auxiliary frame at his pleasure.

To the accomplishment of the general objects stated, and others which will more 35 fully appear, the preferred embodiment of the invention consists in the construction and arrangement of parts to be described, illustrated in the accompanying drawings, and defined in the appended claims. In 40 said drawings,

Figure 1 is a top plan view of the machine constructed in accordance with the invention.

Fig. 2 is a front elevation of the machine.

Fig. 3 is a cross-sectional view of the machine.

Fig. 4 is a side view of the control lever, and

Fig. 5 is a front view of the same.

In the drawings, 1 generally designates a rectangular frame consisting of comparatively long, transverse beams 2, and shorter longitudinal beams 3, interconnecting said first mentioned beams. The frame 1 in the present modification is supported by a pair

of wheels 4, but it is within the scope of the invention to provide a greater number of wheels and to increase accordingly the length of the machine, if so desired. The 60 longitudinal beams 3 are provided on the under-side with depending journal boxes 5, to receive the axle 6 upon which the supporting wheels 4 are mounted, and which axle is formed integral with a collar 7 abutting 65 against the inner side of the journal box 5 so as to prevent displacement of the axle in the journal box in longitudinal direction. The protruding end 8 of the wheel axle is bent upwardly to form an angle of 90 degrees with the other portion of the axle, for a purpose presently to be described. Intermediate the transverse beams 2 of the main or carrying frame 1 of the machine, a cross-beam 9 is provided which at its terminal 70 portions is formed with apertures to permit passage of the upstanding ends 8 of the wheel axle for the purpose of procuring guiding means for the cross-piece 9, when the latter—as will hereinafter appear—is 80 raised or lowered. The cross-beam 9 carries a bolt 10, to which is secured the auxiliary frame, generally designated by 11, and which comprises the longitudinal beams 12 interconnected by a plurality of rods or 85 shafts 13, spaced apart and serving as carriers for an equal number of scraper plates 14. As will be obvious from Figs. 1, 2 and 3, the auxiliary frame 11 is connected to the bolt 10 of the cross-piece 9 by means of a 90 four-armed bracket 15, the terminal portions of the arms being secured to the longitudinal beams 12 of the auxiliary frames by means of bolts, wooden screws, or any other suitable or approved fastening means. The 95 scraper plates 14 are suspended from the shafts 13 by means of fastening pieces 16, which are secured at one end to the scraper plate in any approved manner, while their other ends are bent around the shafts 13 to 100 form a sleeve thereon. Thus it is seen that the scraper plates are freely suspended from the shafts 13 and are capable of oscillating forwardly and backwardly. In order to maintain a resilient, but nevertheless sufficient engagement between the scraper plates and an abutment or ridge of earth to be removed, springs 17 are arranged both at the intermediate portion of the shaft 13 and the terminal portions thereof, the ends whereof 110 contact with the front and rear sides of the scraper plates respectively. This means of

securing the scraper plates insures a sufficient engagement with a slight resistance to be removed, without, however, making the yielding of said plates impossible when an unusually hard resistance, such as a buried stone or a piece of iron, is encountered. The auxiliary frame 11 is adapted to be raised or lowered or turned about the bolt 10 by proper manipulation of a lever 18 arranged 5 in proximity to the seat 19 of the driver or operator, so that the aforementioned adjustments may be conveniently effected by the driver while seated. The lever 18, as shown in Figs. 4 and 5, is mounted upon a pin 20 journaled in boxes 21, 21. A weight 22 is suspended from the lever 18 to normally maintain the same in upright or vertical position.

A pair of levers 23 and 24 are loosely mounted on the pin 20, each of which comprises an upper portion 25 and a lower portion 26. The upper portion 25 terminates in a sleeve, through which the lower portion 26 projects, and a spring 27 is interposed between the upper end of the lower portion and the adjacent side of the sleeve portion of the upper part, so as to maintain the upper and lower parts of each lever constantly in engagement. The upper parts 25 20 are provided with a tooth 28 adapted to enter the recesses of a notched quadrant 29 and 30 respectively, whereby the levers 23 and 24 are secured in adjusted position. The lower parts of the levers 23 and 24 are 25 forked to receive links 31 and 32. The lever 18 is equipped with locking and release handles 33 and 34 at its upper end, and rods 35 and 36 respectively interconnect the handles with pawls 37 and 38 extending 30 through an enlarged central portion of the lever 18, and slidably fitted therein. The pawls 37 and 38 are equipped with a tooth 39 and 40 respectively, and springs 41 and 42 interposed between lugs of the lever 18 35 and the pawls serve to maintain said pawls in inoperative or disengaged position. When it is desired, for instance, to manipulate lever 23 and thereby actuate the link 31, the handle 33 is forced against the lever 18, 40 whereby the tooth 39 of the pawl 37 is raised and the upper portion 25 of the lever 23 is released from the notched quadrant 29. Together with the raising of the upper lever portion 25, the main lever 18 is interlocked with said portion, so that oscillation 45 of the main lever simultaneously causes a movement of the lever 23. The link 31 extends backwardly from the lever 23 and is articulated with a lever 44 secured to a square 50 shaft 45 provided with terminal rounded portions journaled in bearings 46 provided on the longitudinal beams 3 of the main frame 1. The square shaft 45 at one end has an arm 47 connected by a link 48 to a 55 double lever 49 pivotally mounted interme-

diate its ends on the bearing 46. The free end of said lever 49 is secured to the cross piece 9. From the foregoing it is obvious that upon oscillation of the lever 18, when the lever 23 is locked thereto, the link 31 is 70 actuated to move forwardly or backwardly, so that the square shaft is forced to rotate with its rounded terminal portions in the journal bearings 46 and simultaneously the 75 arm 47 of the shaft rocks the lever 49 upwardly and downwardly, in accordance with the direction of movement of the lever 18, whereby the cross-piece 9 is raised or lowered. The auxiliary frame being secured to the cross-piece by means of the bracket and 80 the bolt 10, follows the movement of the cross-piece 9, so that the scraper plates 14 will be raised or lowered at the pleasure of the operator. The link 32, articulated with the lower part of the lever 24, is secured to 85 a lever 50 fitted to a square portion 51 of the frame bracket. When the lever 24 is actuated to move forwardly or backwardly, the arm 50 is turned in a horizontal plane, so that the auxiliary frame, and consequently the associated scraper plates will be 90 placed at an angle with respect to the normal transverse position.

While the drawings illustrate the preferred embodiment of the invention, it is understood that alterations and changes may be made in the construction and arrangement of the parts. I, therefore, do not intend to confine myself to the details exactly 95 as shown, but want to avail myself of all such departures which fairly fall within the scope of my invention, as pointed out in the appended claims.

I claim:

1. In a grading machine, the combination 105 with a wheeled frame, of an auxiliary frame, scraper plates suspended therefrom, a cross-piece rotatably carrying said auxiliary frame, said cross-piece being adjustably supported by the wheeled frame, a lever, connections between said lever and said cross-piece, and separate connections between said lever and the auxiliary frame.

2. In a grading machine, the combination 115 with a wheeled frame, of an auxiliary frame, scraper plates freely suspended therefrom, means for maintaining the scraper plates in operative position, a cross-piece rotatably carrying said auxiliary frame, said cross-piece being adjustably supported by the 120 wheeled frame, a lever, connections between said lever and said cross-piece, and separate connections between said lever and the auxiliary frame.

3. In a grading machine, the combination 125 with a wheeled frame, of an auxiliary frame, scraper plates suspended therefrom, a cross-piece rotatably carrying said auxiliary frame, said cross-piece being adjustably supported by the wheeled frame, a lever, con- 130

nections between said lever and said cross-piece, and connections between said lever and the auxiliary frame, said lever being adapted to selectively actuate said first and second named connections.

4. In a grading machine, the combination with a wheeled frame, of an auxiliary frame, scraper plates suspended therefrom, a cross-piece rotatably carrying said auxiliary frame, said cross-piece being adjustably supported by the wheeled frame, a pair of levers placed in juxtaposed relation, said levers having connections with said cross-piece and said auxiliary frame respectively, and a manipulating lever interposed between said pair of levers and adapted to be selectively coupled with said levers.

5. In a grading machine, the combination with a wheeled frame, of an auxiliary frame, scraper plates suspended therefrom, a cross-piece rotatably carrying said auxiliary frame, said cross-piece being adjustably supported by the wheeled frame, a pair of levers each comprising an upper and a lower part, said upper part being yieldingly retained in fixed relation to said lower part, means for locking the upper parts of said lever in adjusted position, a third lever interposed between said pair of levers, and means on said third lever for disengaging the upper parts of said pair of levers and interlocking the same with said third lever, substantially as described.

6. In a grading machine, the combination with a wheeled frame, of an auxiliary frame, scraper plates suspended therefrom, a transverse shaft journaled in the main frame, a

double lever supported on said main frame, connections between said transverse shaft and one end of the double lever, the other end of said double lever being connected to said cross-piece, a manipulating lever, connections between said lever and said transverse shaft, and connections between said manipulating lever and the auxiliary frame, substantially as described.

7. In a grading machine, the combination with a wheeled frame, of an auxiliary frame, scraper plates suspended therefrom, a cross-piece, a pivot pin connecting said auxiliary frame to said cross-piece, a transverse shaft journaled in bearings of the main frame, a double lever pivotally supported on the main frame, connections between said transverse shaft and one end of said double lever, the other end of the double lever being connected to said cross-piece, guiding means for said cross-piece, a pair of levers placed in juxtaposition, each of which comprises an upper and a lower part, notched quadrants for the upper parts of said pair of levers and adapted to receive a tooth of said upper parts, a manipulating lever interposed between said pair of levers and adapted to selectively disengage the upper parts from said notched quadrant and to simultaneously interlock said upper parts with said manipulating lever, and connections between said pair of levers of said auxiliary frame and said transverse shaft respectively.

In testimony whereof I hereunto affix my signature.

XAVIER F. COUNARD.
